UNITED STATES PATENT OFFICE

KNUTE OMHOLDT, OF IRON MOUNTAIN, MICHIGAN, ASSIGNOR OF ONE-FOURTH TO
LEO H. MORTENSEN, OF IRON MOUNTAIN, MICHIGAN

VISE

Application filed August 3, 1931. Serial No. 554,921.

This invention relates to a vise and has for the primary object, the provision of a quick and convenient adjusting means for the jaws of the device whereby the jaws may have a wide range of adjustment relative to each other for accommodating objects of different sizes or dimensions and when adjusted to an object will firmly hold the same against accidental movement.

10 Another object of this invention is the provision of means for varying the gripping action of the jaws on an object after being adjusted thereto whereby the liability of the object slipping within said jaws is obviated and also permits the gripping of objects firmly which objects may be constructed of yieldable material.

With these and other objects in view, this invention consists in certain novel features 20 of construction, combination and arrangement of parts to be hereinafter more fully described and claimed.

For a complete understanding of my invention, reference is to be had to the following description and accompanying drawings, in which

Figure 1 is a perspective view illustrating a vise constructed in accordance with my invention.

30 Figure 2 is a bottom plan view illustrating the same.

Figure 3 is a sectional view taken on the line 3—3 of Figure 2.

Figure 4 is a similar view taken on the line 4—4 of Figure 2.

Figure 5 is a transverse sectional view taken on the line 5—5 of Figure 4.

Figure 6 is an end view illustrating the operating handle for tensioning the jaws 40 after being adjusted to an object.

Figure 7 is a detail sectional view taken on the line 7—7 of Figure 6.

Figure 8 is a detail sectional view illustrating an adjusting rod operating in conjunction with the handle for tensioning the jaws when adjusted to an object.

Referring in detail to the drawings, the numeral 1 indicates an elongated base having formed thereon pairs of ears 2 apertured 50 to receive fasteners for securing the base to

a support. The base 1 has formed integral with one end thereof a stationary jaw 3 adapted to cooperate with a movable jaw 4 in gripping objects. The base 1 has formed therein a chamber 5 opening outwardly 55 through the bottom of said base and one end and has opposite walls thereof grooved to receive ribs 6 formed on attaching elements or plates 7 that form an integral part of the movable jaw 4. The opposing faces of the 60 elements 7 are provided with grooves to receive ribs 8 formed on an adjusting element or plate 9, the forward edge of which is detachably secured to an adjusting rod 10. The adjusting rod extends through the movable jaw as shown in Figure 3 and has detachably secured to its outer end a head 11. A sleeve 12 is mounted within the movable jaw and slidably receives the rod 10 and forms a seat for one end of a coiled spring 13 70 mounted upon the rod while the opposite end of the spring seats against a collar 14 secured to the rod. The spring 13 normally urges the rod 10 in one direction.

The plates or elements 7, 8 and 9 have 75 formed thereon a series of teeth 15 to be engaged by teeth 16 of resilient dogs 17 secured to the base as shown at 18. The free ends of the dogs are bevelled as shown at 19 to be engaged by an actuating device 20 carried by the base 1 whereby said dogs may be disengaged from the teeth 15 for the purpose of freeing the movable jaw that the latter may be adjusted relative to the stationary 80 jaw for the purpose of gripping objects of different sizes or dimensions. The operating means consists of a rod 21 journaled in the base and having a portion thereof bent angularly to form a handle 22 operating within a bracket or keeper 23 mounted upon the base. Secured to the rod 21 is a dog engaging plate 24 so that when the handle 22 is moved in one direction or into a position as shown in dotted lines in Figure 1, the dogs 17 will be disengaged from the teeth 15 of 85 the plates or elements 7 and 8.

A handle or lever 25 is pivoted to the movable jaw 4 as shown at 26 and is provided with a slot 27 to receive the adjusting rod 10 under the head 11 and one face of the han-

dle is inclined to form a cam surface 28 about the slot 27 while the inner face of the head 11 is inclined to form a cam surface 29.

In operation, the lever 25 is disengaged from the adjusting rod 10 and an object is placed between the jaws and said jaws adjusted against the object. With the handle 22 in a full line position as shown in Figure 1, the movable jaw will be prevented from moving away from the stationary jaw or the object gripped between said jaws. The lever 25 is swung downwardly bringing the cam face 28 thereof into engagement with the cam face 29 of the head 11 causing an endwise movement of the adjusting rod against the tension of the spring 13. As the plate or element 9 is held against endwise movement with the adjusting rod, the movable jaw is forced toward the stationary jaw to increase the gripping action upon the object. The cam faces 28 and 29 permits the tension of the movable jaw upon the object to be varied as desired. The elements or plates 9 have formed therein grooves 30 to receive the inner ends of set bolts 31 threaded to the base for the purpose of limiting the adjustment of the movable jaw relative to the fixed jaw.

While I have shown and described the preferred embodiment of my invention, it will be understood that minor changes in construction, combination and arrangement of parts may be made without departing from the spirit and scope of my invention, as claimed.

Having thus described my invention, what I claim is:

1. A vise comprising a base, a fixed jaw carried by said base, a movable jaw for cooperation with the fixed jaw for gripping objects of different sizes, a shank on the movable jaw, spaced elements carried by said shank and slidably mounted in the base, a plate slidably mounted between said elements, teeth formed on said elements and plate, tension dogs carried by said base for engagement with the teeth, a control means carried by the base for disengaging the dogs from the teeth, a cam shaped element connected to the plate, and a second cam shaped element pivoted to the movable jaw for cooperating with the first named cam shaped element in tensioning the movable jaw against an object after being adjusted thereto.

2. A vise comprising a base, a fixed jaw carried by said base, a movable jaw cooperating with the fixed jaw for gripping objects of different sizes, a shank on the movable jaw, spaced elements carried by said shank and slidably secured to the base, a plate slidably mounted on said elements, teeth on said elements and plate, tensioned dogs carried by said base for engagement with the teeth, operating means carried by the base to disengage the dogs from the teeth, a rod secured to said plate and extending through the shank and movable jaw, a cam shaped head on said

rod, tension means for said rod, and a slotted lever pivoted to the movable jaw and having a cam shaped face to engage with the cam shaped head for tensioning the movable jaw against an object after being adjusted thereto. 70

3. A vise comprising a base, a fixed jaw carried by said base, a movable jaw cooperating with the fixed jaw in gripping objects of different sizes and slidably connected to the base, teeth on the movable jaw, tension dogs 75 to engage said teeth, a plate slidably relative to said base, teeth on said plate, a dog for engaging the last named teeth and carried by said base, means associated with the movable jaw and the plate for tensioning said movable jaw against an object after being adjusted thereto, and an operating means journaled to the base for engaging said dogs simultaneously to disengage them from their respective teeth. 80

In testimony whereof I affix my signature.
KNUTE OMHOLDT.
